FELIX R. BELKIN

INVENTOR

BY John P. Mizorow

ATTORNEY

UNITED STATES PATENT OFFICE.

FELIX R. BELKIN OF BROOKLYN, NEW YORK.

AUTOMATIC ELECTRIC IGNITER.

Application filed March 26, 1924. Serial No. 702,027.

To all whom it may concern:

Be it known that I, FELIX R. BELKIN, citizen of Russia, and resident of Brooklyn, in the county of Kings and State of New York, have invented certain new and useful Improvements in Automatic Electric Igniters, of which the following is a specification.

My invention relates to electric apparatus for igniting the combustible mixture in gas or liquid burners.

The object of my invention is to provide an apparatus which would automatically ignite the combustible mixture by means of an electric spark when the handle of a mixture admitting valve is turned to an operative position.

I also provide a means to render the electric circuit inoperative during the time when the valve handle is being turned back so as to close the valve for the combustible mixture.

In order to render the operation of my device more certain I arrange for a series of successive sparks to be produced at the electrodes during the time when the valve handle is being moved.

My invention is more fully described in the accompanying specification and drawing in which—

Fig. 1 is a plan view of my device in connection with a multiple gas burner, the electric circuit being shown diagrammatically. Fig. 2 is a side elevation of the electric contacts shown partly in section, Fig. 3 is an end view of same, Fig. 4 is an enlarged sectional view of the burner with electrodes, and Fig. 5 is a modified arrangement of sparking points especially adapted for burners developing temperature, the electrodes being movable and electrically operated.

My automatic igniter consists of sparking points 1 and 2, points 1 being directly connected to the metal body of the burner 36 and attached by means of clamping screws 4. The points 2 are insulated from the burner by means of heavy insulation 5 adapted to withstand high temperatures and a high voltage. For instance, it may be made of asbestos with rubber or ozokerite inside. The points 2 may be simply formed as the ends of the cables 6.

These cables 6 extend from contact points

7 placed on an insulating block 8 in a switch box 9 and arranged in a circle around the center of a pin 10. A cylinder 11 is rotatively mounted on the pin 10 and is provided with a lug 12 supporting an insulation block 13. This block is provided with a high tension contact brush 14. This brush is adapted to touch the high tension contact points 7 which are individual for each sparking point, connecting these contact points 7 with a common contact plate 15. A cable 16 connects this contact plate with one end of a high tension or secondary coil 17.

The other end of the insulation block 13 is provided with a low tension brush 18 adapted to touch successively low tension contact points 19, connecting them with a common low tension contact plate 20. A lead 21 connects this contact plate with one end of a low tension or primary coil 22.

The other ends of the coils 17 and 22 may be connected together having a common lead 23 to a grounding point 24 on a burner 36. This lead 23 is also connected with one pole of a battery (or similar source of the electric current) 26. The other terminal of this battery is connected with the common contact plate 20 by means of a lead 25.

The insulation block 8 is attached to the bottom of the switch box 9 which is supported on a valve 27 which controls the flow of a fuel to the burner. The valve handle 28 has a lug 29 adapted to press against a lug 29' on the cylinder 11. This lug 29' is pivotally mounted on a pin 30 and is supported underneath with a short lug 31.

A second lug 32 is provided on the valve handle 28 in order to produce a second series of sparks when the valve handle is moved towards opening the valve. If necessary, of course, three or four of such "repeating" lugs may be used. A retrieving spring 33 is adapted to move the contact cylinder 11 into an inoperative position.

A pipe 34 leads the fuel to the valve. A pipe 35 connects the valve with the burner 36 which may consist of a series of concentric tubes with narrow slits 37 from which the gaseous fuel escapes in the form of jets to be ignited. Similar rows of slits 38 may distribute the flame from one ring 36 with the other.

I prefer to make the apertures 37 in the

form of narrow slits in order to reduce the spark gap between the points 1 and 2. This enables me to use a moderate voltage for a secondary circuit, reducing also the flame temperature at the spark gap thereby extending the life of the sparking points 1 and 2.

The operation of my device is as follows. By moving the handle 28 the valve 27 is

10 opened, and the gas or similar combustible mixture is admitted to the burner 36. The lug 29 comes in a contact with the lug 29' turning the cylinder 11 and moving the contact brushes 14 and 18.

15 The brush 14 comes in a contact with the contact point 7 and with the plate 15 thereby closing the high tension circuit from the coil 17 through the spark gap 1-2. The low tension or primary circuit is closed at the same time from the source of current 26. 20 through the primary coil 22 when the brush 18 comes in a contact with the first low tension contact point 19 and a plate 20.

25 The contact points 19 are made in the form of springs, and the primary circuit is quickly broken with the further movement of the brushes. The interruption of the primary circuit causes a secondary or high tension current to be induced in the coil 17, 30 and this current is discharged in the form of a spark through the first spark gap. The nearest jet of gas is then ignited, the flame rapidly communicating also to all the other jets.

35 With the further movement of the handle 28 the primary current is again closed and interrupted on the second contact point 19, thereby sending a secondary discharge through the second high tension contact 40 point 7 and into the second spark gap. In this manner the combustible mixture will be ignited if it failed to catch fire from the first spark.

45 A third spark may be set with the further handle movement. Then the lugs 29 and 29' become separated, and the retrieving spring 33 moves the contacts back, causing again one or more sparks to be produced, until the second lug 32 gets in contact with the lug 50 29' and begins to turn the cylinder 11 with the contact brushes. More sparks will be produced accordingly rendering the gas ignition absolutely certain.

55 When the handle 28 is moved back to close the valve, then the lugs 29 and 32 simply raise the lug 29' on its pivot without moving the cylinder 11, so that no sparks will be produced when they are not needed. This arrangement is made in order to economize in the current consumption.

60 Fig. 5 represents a modified arrangement of the spark gap which is used in cases when the flame is very hot, like in liquid fuel burners, or when the burner aperture is 65 large.

The gap points 1 and 2 are attached to insulation blocks 39 pivotally mounted on pins 40. A spring 41 keeps the gap points separated and away from the high tension contacts 42.

70 An iron armature 43 is attached to the blocks 39 on links 44 and is adapted to be actuated by an electromagnet 45 which is included in the primary circuit in the lead 21.

75 With this arrangement every time when the primary circuit is closed, the magnet 45 attracts the armature thereby bringing the gap points in a contact with the high tension points 42 thereby causing the spark to 80 jump between these gap points 1 and 2. With the circuit interrupted the gap points move apart under action of the spring 41 and away from the flame.

85 A dash pot 46 may be connected with one of the blocks 39 with a plunger 47 on the other in order to retard the movements of the gap points.

90 Important advantages of my automatic electric igniter are that it is adapted to 95 ignite the fuel in a burner automatically and every time when the fuel admitting valve is opened, thereby eliminating a danger of an accidental opening of the valve when the fuel is not lighted; for instance as it may happen in an ordinary gas stove with the children playing near it. With my arrangement the valve cannot be opened without igniting the fuel at the same time. The ignition is also made positive for practically 100 all degrees of opening of the valve.

I claim as my invention:

1. In an automatic electric igniter, the combination with a burner, fuel nozzles on said burner, a plurality of electrodes on said burner in a cooperative relation with said nozzles, a valve adapted to control the fuel admission to said burner, an induction coil, leads connecting said coil with said electrodes, a plurality of contact points formed between said leads, a sliding contact brush adapted to engage said contact points, a rotatively mounted cylinder supporting said sliding contact brush, a handle on said valve, a plurality of lugs on said valve adapted to turn said cylinder when said valve is being opened, a retrieving spring for said cylinder, and means to prevent the movement of said cylinder when said valve is being closed.

110 2. In an automatic electric igniter, the combination with a burner, fuel nozzles on said burner, a plurality of electrodes in a cooperative relation with said nozzles, a valve adapted to control the fuel admission to said burner, an induction coil having a primary and a secondary winding, a plurality of contacts for said primary winding, a plurality of contacts for said secondary winding, and means to successively close 115 120 125 130

said primary and said secondary contacts, said means being controlled by the movement of said fuel valve.

3. In an automatic electric igniter, the combination with a burner, fuel nozzles on said burner, a plurality of electrodes in a cooperative relation with said nozzles, a valve adapted to control the fuel admission to said burner, an induction coil having a primary and a secondary winding, a plurality of contacts for said primary and said

secondary windings, a sliding member adapted to successively close said contacts, means to operate said sliding member by said valve when said valve is being opened, 15 a retrieving means for said sliding member, and means to render said sliding member inoperative when said valve is being closed.

Signed at borough of Brooklyn, in the county of Kings and State of New York, 20 this 22 day of March, A. D. 1924.

FELIX R. BELKIN.
